OIL BURNER FOR TOBACCO CURING BARNS

Charles C. Granger, Henderson, N. C.

Application May 27, 1949, Serial No. 95,747

2 Claims. (Cl. 158—91)

1

This invention relates to certain new and useful improvements in oil burners and has reference, more particularly stated, to one which is admirably well designed and suited for efficient performance when used in a tobacco drying and curing barn, as a general rule, in combination with necessary stack and flue means and several other burners of the same construction.

A primary object of the invention is to structurally, functionally and otherwise improve upon drying and curing burners which have been devised by others for the same purposes by providing a novel construction which, even though relatively small in size as burners go, is actually a heavy duty appliance in that it draws in moistened air from moist tobacco and, as a result, develops a good flame with resultant effective heating and rapid tobacco drying.

Another object of the invention is to provide a structure which is susceptible of ready and economical manufacture and sale and is such in overall construction that it makes for more expedient assembling and installation and, thereafter, provides for the making of ready repairs and replacements.

More specifically, novelty has to do with the specific construction of the burner unit on the one hand and the complemental housing on the other hand, said unit being singly and collectively novel.

In carrying out my aims I provide a one-piece casting with supporting legs, a channel forming an oil ring and an outstanding flange with an outer marginal lip providing an oil overflow and drainage trough.

Then, too, novelty is predicated upon a simple readily attachable and detachable cone with adapting lugs which cone functions as an efficient flame spreader.

What is more, novelty has to do with a triple part housing characterized by an annular base which sits on the floor and which supports an attachable air intake plate which latter part, in turn, serves to support a frusto-conical hood which constitutes an effective flue insert or fitting.

Other objects and advantages will become more readily apparent from the following description and the accompanying illustrative drawings.

In the drawings:

Figure 1 is a perspective view of a tobacco barn-type oil burner constructed in accordance with my inventive ideas.

Figure 2 is a perspective view of the oil burner per se.

2

Figure 3 is a vertical sectional view on the line 3—3 of Figure 1 looking in the direction of the arrows.

The burner proper is denoted by the numeral 5 and this supports the flame spreader 6 and said parts 5 and 6, when assembled, are jacketed within the confines of the triple-part housing.

The burner 5 is a one-piece casting and is characterized by an oil ring which takes the form of a channel whose inner wall is denoted at 7 and outer wall at 8. Projecting horizontally and radiating from the outer wall and in a plane with the bottom of the channel is a circular flange 9 having a marginal upstanding lip 10 defining an oil overflow and drainage trough. The supporting feet or legs are denoted by the numeral 11. The oil delivery pipe or line (which attaches to an oil drum) is denoted at 12 and the drainage pipe or line 13 and the first pipe 12 connects with the oil ring and the second pipe 13 with the oil overflow trough as brought out in Figure 3. Pipe 13 attaches, at its opposite end, with an oil sump (not shown). The conical air deflector 6 is of a basal diameter about equal to the diameter of the air flow passage 14 of the oil ring and the base of said cone is spaced above the upper edge of the wall 7 by way of lugs 15 which telescope into the ring defined by the flange 7 and also serve to frictionally hold the cone in place and at the same time provide the air circulating space as illustrated in Figure 3.

The housing is of three-part construction and characterized by a base or annulus 16 which is of the approximate diameter shown in Figure 3 and which surrounds and is spaced from the lip 10. The upper edge portion of the base or annulus 16 is rabbeted to provide a ledge 17 and this serves to seat the outer marginal edge or periphery of the annular air inlet collar or plate 18. The air inlet holes in the plate are denoted by the numeral 19. The inner peripheral edge portion of the plate has an upstanding endless shoulder or bead 20 defining a ledge 21 which seats the base of the truncated cone or hood 22. The cone or hood 22 constitutes a flue adapter or coupling which, in practice, telescopes into a coacting downturned end of one branch of a flue assembly (not here shown). It will be noted that the inner peripheral edge of the plate 18 is spaced outwardly from the outer channel wall 8 to provide a further passageway for incoming air. The arrows indicate approximately how the moistened air enters and circulates and thus it will be understood that since the base 16 is imperforate the air is drawn in by way of the plate

openings 19 on a plane approximately even with the upper open top of the oil ring. Consequently, we have a conical deflector at the axial center of the flue adapter 22, an oil ring (7 and 8) of an outside diameter less than the diameter of the base of the flue adapter 22 and a trough forming flange 9 of an outside diameter greater than the diameter of the adapter 22 and of considerably less diameter than the outside diameter of the plate 18. Thus, the parts are precision made for correct mechanical coaction with one another when assembled as shown in the drawings, particularly Figure 3. As previously stated, several of these burners are used in ordinary sized tobacco barns and they collectively take in the moistened air from the correspondingly moist tobacco and insure the development of a high sweeping flame, the production of efficient heat and rapid drying and consequent curing of the suspended tobacco. There are many and varied styles and types of tobacco curing burners and for this reason I find it unnecessary to dwell upon how these burners function to bring about effective tobacco curing results. I am concerned primarily with the structural details and their relationship and my claims are presented accordingly.

When installing, be sure to level burner in order to maintain a balanced flame around same. This can best be done by turning oil control valve on until oil fills burner plate, then adjust until oil is level in plate.

When lighting the burner, be sure that safety cut-off valve is open and properly connected to cable and fuse link. Open the oil control valve and wait until oil can be seen in burner plate. Turn control valve back to low fire, saturate a small piece of paper in oil and drop it under burner. Allow about ten minutes for the burner to warm up before turning control valve to a higher heat stage. Never light the burner while it is hot, let it cool until the bare hand can be held on burner.

To raise the heat properly open oil control valves gradually allowing two or three hours for heat to reach the desired stage, each time temperature can be raised in either side of barn by raising controls separately.

Changes in shape, size, materials and rearrangement of details and parts may be resorted to in actual practice, so long as they do not depart from the spirit of the invention or the scope of the appended claims, as is well understood.

Having described the invention, what is claimed as new is:

1. In a portable tobacco barn oil burner of the class described, a unitary burner casting embodying an annular channel circumscribing and forming an endless oil ring, the inner wall of said channel defining an unobstructed circular air circulating space, said channel having means whereby a fuel oil delivery pipe may be attached to the bottom of said channel, a circular horizontal imperforate flange integral with and on a plane with said bottom and radiating from the outer wall of the channel and having an upstanding outer marginal lip combining with said flange in defining a relatively shallow oil overflow and draining trough, supporting legs in-

tegral with, underlying and depending from said flange, an air deflector cone, the base of the latter being of a diameter slightly greater than the aforementioned air space and having basal lugs telescoping and fitting frictionally in contact with the inner wall of said channel, and separate knockdown housing means for said burner embodying a truncated conical flue adapter lined up with the burner, said flue adapter being of a basal diameter larger than said channel and less than the diameter of said flange, support means spaced radially from and surrounding said oil ring and trough, said means being of a height which terminates on a plane with the upper open end of said channel, and a flat plate between said support means and flue adapter, said plate being disposed in a plane with the upper open top of said channel.

2. In a portable tobacco barn oil burner of the class shown and described, an oil burner embodying a one-piece casting, the latter including an annular channel forming an open-top oil ring, said channel having inner and outer vertical walls, a circular horizontal flange integral with and radiating from the outer wall of said channel and having an upstanding marginal lip and defining an oil overflow and draining trough, supporting legs attached to and depending from said flange, an inverted air deflector cone, the latter having basal lugs telescoping and fitting frictionally in contact with the upper edge portion of the inner wall of said channel, the base of said cone being spaced above said upper edge, a flat annular plate disposed in a horizontal plane approximately even with the plane of the upper open side of said channel and overlying said trough in vertically spaced parallelism and having its outer marginal edge projecting beyond the corresponding marginal edge of said trough and being provided with air circulating holes, means supporting the outer peripheral edge of said plate in the stated plane, the inner peripheral edge of said plate being in spaced concentric relation in respect to the outer wall of said channel and the upper surface of said inner edge being provided with an upstanding circular rib spaced radially outward from said inner peripheral edge and coacting with the latter in defining a ledge, and a truncated conical flue adapter having its broad basal end resting on said ledge and held in place on the latter by way of the encircling upstanding rib, said adapter surrounding said deflector cone in spaced concentric relationship and having its truncated end extending to a position well above the apex of said cone.
